WALTER B. SCHOEPLER, OF NEW YORK, N. Y.

GRID LEAK.

Application filed June 3, 1924. Serial No. 717,462.

This invention relates generally to electrical resistance elements being intended more particularly for embodiment in the high resistance devices of radio apparatus which are commonly known as grid leaks, and which provide high resistance paths around the grid condenser to maintain the grid at its normal condition.

The invention has for an object the provision of a novel and improved form of grid leak which is of simple construction and can be manufactured at small cost.

For further comprehension of the invention, and of the objects and advantages thereof, reference will be had to the following description and accompanying drawing, and to the appended claims in which the various novel features of the invention are more particularly set forth.

Fig. 1 of the drawing is a longitudinal sectional view showing my improved grid leak.

Fig. 2 is a transverse sectional view taken on the line 2—2 of Fig. 1.

Fig. 3 is a like view taken on the line 3—3 of Fig. 1.

Fig. 4 is a detail perspective view of one of the contact clips.

Fig. 5 is a like view of one of the end caps.

Fig. 6 is a longitudinal sectional view showing a modified construction.

Fig. 7 is a like view to Fig. 6 and showing a further modification.

Fig. 8 is a modified arrangement of the clip, and cap in which the clip retains the cap in place.

Referring now to the drawing, my improved grid leak comprises an insulating tube or casing 10 which is preferably made of glass, this tube being formed with both ends open for insertion of the resistance elements, these ends being afterward closed by suitable caps, or ferrules. The resistance element which I make use of comprises a strip 12 of paper which is impregnated with a suitable chemical preparation to give it the required resistance, and which may be of a width to extend about one-quarter way around the tube, although the width may be varied, or arranged as desired to suit different conditions. The paper is of substantially the same length as the tube, being here shown as slightly shorter, and is inserted in the tube in contact with the inner surface thereof.

This paper is engaged, adjacent opposite ends thereof, by contact clips 15 which are

made of copper or other metal strips and which comprise an inner portion engaging in the tube and laterally expanded to bear on opposite sides of the tube, and an outer portion which straddles the end of the tube wall. To form this expanded portion the clips are preferably bent, as seen in side elevation, to a V-form as at 15' the apex of this V-portion bearing on one side of the tube, while the inner end of the clip bears on the paper as shown, the intermediate portion of the clip bearing on the side of the glass tube diametrically opposite to that against which the apex of the V-portion bears. The outer end portion of the clip is bent backwardly over the body of the clip as at 15" and engages over the end of the tube 10, this end portion being preferably rounded as seen in cross section in Fig. 3 of the drawing to fit snugly upon the tube.

The clips are held in place by means of the caps or ferrules 18 which are fitted over the ends of the tube and which engage the turned back ends 15" of the clips. As shown clearly in Fig. 4 of the drawing the turned back end of each clip is inclined, from its root to its tip, in the direction of the body of the clip so that when the cap or ferrule is mounted on the tube it will bear in an inward direction on the projecting end of the clip and by such action tend to force the inner end of the clip against the resistance strip 12, the apex of the V-part of the clip acting as an abutment or fulcrum to transfer the inward pressure on the outer end of the clip to an outward pressure on the inner end of the clip, thereby binding the latter more securely against the paper strip 12. The caps or ferrules are preferably secured in place by means of a suitable cement.

In the form of the invention shown in Fig. 6 of the drawing I make use of the tube 10, impregnated paper 12, clips 15 and ferrules 18 as above described. In this case however, a cork disk 20 is inserted into the tube and positioned therein between the ends thereof, while copper or other metal strips 21 extend from the clips to the said disk, these metal strips being engaged by the inner ends of the clips in the manner above pointed out. The provision of these additional metal strips enables the device to be set to any desired resistance.

In the form of the invention shown in Fig. 7 I make use of the tube 10 and paper 12. At one end of the tube I provide the clip 15

which bears on the paper and is secured in place as above set forth by the cap 18. To co-operate with the clip in engaging the paper I provide in this case an elongated metal strip 25 which extends longitudinally through the tube and which is formed at its inner end with a V-portion 25' whereby it is caused to bear at its end on the strip 12, the apex of the V-part 25' bearing on the diametrically opposite side of the tube. The other end of the tube is closed by a cap or ferrule 18' which is formed with a suitable aperture through which the strip 25 passes. After the strip has been adjusted with relation to the tube to produce the desired resistance, the proper adjustment of the strip being determined by suitable tests, the strip is then welded to the ferrule 18', the ferrules on both ends of the tube being cemented in place on the latter.

In Fig. 8 I have shown a modified arrangement of the clip and cap in which the clip retains the cap in place. In this construction the turned back outer end 15^c of the clip engages behind an outturned lip 10^c on the tube, while the cap has an inturned flange 18^c which engages behind a resilient hump 15^d on the clip end.

Having thus described my invention what I claim as new and desire to protect by Letters Patent of the United States is as follows:

1. The combination in a grid leak having a tube, a resistance strip therein, and end caps, of a clip formed with an inner portion engaging in the tube, and laterally expanded to bear on diametrically opposite sides of said tube, and an outer portion which straddles the end of the tube wall, said inner portion being bent to a V-form, the apex of this

V-portion bearing on one side of the tube, while the part opposite the apex bearing on the diametrically opposite side of the tube against said resistance strip.

2. The combination in a grid leak having a tube, a resistance strip therein, and end caps, of a clip formed with an inner portion 45 engaging in the tube, and laterally expanded to bear on diametrically opposite sides of said tube, and an outer portion 50 which straddles the end of the tube wall, said inner portion being bent to a V-form, the apex of this V-form bearing on one side of the tube, while the part opposite the apex bearing on the diametrically opposite side of the tube against said resistance strip, said outer portion being clamped by the said end caps, whereby the apex of the V-portion of the clip acts as a fulcrum to transfer the inward pressure on the outer end of the clip to 60 an outward pressure on the inner end of the clip.

3. An electrical resistance element comprising a tube, a resistance strip therein, a substantially V-shaped clip bearing on said 65 resistance strip and guided about the mouth of said tube, a cap for securing said clip at one end of said tube, a metal strip within said tube extending through the opposite end thereof, a V-part formed with said metal strip adapted to bear on said resistance strip, the apex of said V-part bearing on the diametrically opposite side of said tube, a cap or ferrule through which the extended end 70 of said metal strip is guided and adapted to close the end of said tube through which said metal strip extends.

In testimony whereof I have affixed my signature.

WALTER B. SCHOEPPLER.
